C. P. HIDDEN,
PNEUMATIC DESPATCH TUBE SYSTEM,
APPLICATION FILED JULY 19, 1916.

1,332,895.

Patented Mar. 9, 1920.

UNITED STATES PATENT OFFICE.

CHARLES P. HIDDEN, OF BROOKLINE, MASSACHUSETTS, ASSIGNOR TO THE LAMSON COMPANY, OF BOSTON, MASSACHUSETTS, A CORPORATION OF NEW JERSEY.

PNEUMATIC-DESPATCH-TUBE SYSTEM.

1,332,895.

Specification of Letters Patent.

Patented Mar. 9, 1920.

Application filed July 19, 1916. Serial No. 110,221.

To all whom it may concern:

Be it known that I, CHARLES P. HIDDEN, a citizen of the United States, residing at Brookline, in the county of Norfolk and 5 State of Massachusetts, have invented certain new and useful Improvements in Pneumatic-Despatch-Tube Systems, of which the following is a specification.

This invention relates to pneumatic despatch tube apparatus and it has for one of 10 its principal objects the economization of power in the operation of despatch tube systems while yet insuring a proper transmission of carriers through the tube line 15 with practically unfailing certainty.

In a system of this general character, it has also been my aim to so devise the apparatus as to enable it to meet the conditions of practice wherein it is frequently necessary 20 to employ tube lines of very considerable length; since obviously, the longer the tube lines to be served, the greater the liability of one or more carriers being left inadvertently in the line to the inevitable discom- 25 fort of the users of such apparatus and of the patrons of, for example, stores, wherein it may be used.

Another object of my invention, considered broadly in an aspect thereof which is 30 of general application to pneumatic despatch tube systems wherein variations in the load on the line affect the operation of the air current establishing means, is to prevent what I have hereinafter termed cumulative 35 interaction between said means and the governing or controlling device therefor which acts responsively to said variations.

These and numerous other objects of my invention will be hereinafter more fully 40 considered and the novel combinations of means and elements whereby said objects may be attained, will be more particularly pointed out in the claims appended hereto.

In the accompanying drawing which 45 forms a part hereof and in which like reference characters designate like parts throughout the several views, I have exemplified a preferred embodiment of my invention; but as I am aware of many changes 50 and modifications which may be made herein without departing from the spirit of the

invention, I desire to be limited only by the scope of said claims.

Referring to the drawing:

Figure 1 is a somewhat diagrammatic and 55 partially sectioned representation of a despatch tube system which involves the control of an electric motor by novel instrumen- 60 talities in combination with certain known elements which co-act with said instrumen- 65 talities to effect new and desirable results.

Fig. 2 is a detail of a valve shown in Fig. 1; a portion of said valve and its casing being broken away for purposes of illustration.

Fig. 3 is a detail section of said valve; 65 the section being taken on the line III—III of Fig. 2; and

Fig. 4 is a detail section of a modification of a part of the power controlling device.

It may be stated to begin with that while 70 the system shown merely by way of exemplification is of the so-called vacuum type, the invention in its broader aspects is by no means limited to this particular type of apparatus.

Considering now more particularly the construction which appears in Fig. 1, tube lines have been shown connecting a station A, which may be at the central desk, with a station B, which may, for example, be what 80 is termed in the store service art, a clerk's station.

A transmission tube 1 preferably having a normally open mouth or terminal 1' at A, extends to the station B where the carriers 85 may be delivered from a terminal 2 of known construction. This terminal is provided with the usual valve 3, past which the carriers emerge, and the current of air which passes in the direction of the arrow marked 90 on the tube 1, passes laterally through the conduit 4 in the terminal 2, into the return tube 5. A valve 6 in this latter permits of the insertion of carriers thereinto for despatch from the station B back to the station 95 A. Such carriers are delivered to the usual chute or shelf 7, past a valve 7'; the air current delivered through the tube 5 passing laterally through the terminal casing 8 into the exhaust tube 9 which delivers to a drum 100 10, or the equivalent thereof.

In the present case the drum 10 is in direct

communication with a blower or pump 11, which exhausts the air from the drum and which is driven by an electric motor 12, in known fashion.

- 5 A rheostat 18, of preferably somewhat unusual construction, affords means to vary the field resistance for the requisite control of the motor, and will now be more particularly described. It comprises a rheostat 10 arm 14, pivoted at 15 and carrying a contact 16 adapted to be moved into engagement with any one of the contact plates 17-17'. The resistance in the rheostat is preferably formed of wire 18 coiled or otherwise made 15 to offer increasingly greater resistance between successive connections 19 thereto until a point 18', somewhat above its center, is reached, from either end thereof; the connections 19 leading to the respective contact plates 17-17'. A wire 19' connects the two extremities of the resistance 18 to a lead 20 which runs to a terminal 21 of the motor field coils, while from the second terminal 22 extends a wire 23 which may 25 conveniently be the negative lead to the source of current. I prefer to provide a fixed resistance 19" in the connection 19' so that when in normal operation the motor field will have at least such resistance in it. 30 When the rheostat arm is in its lowermost position, the contact 16 will be out of engagement with any of the plates 17 and no current will flow through the rheostat; but when said arm is moved upwardly, in the manner hereinafter described, until said contact 16 engages the lowermost plate 17', the field circuit is then completed but with a minimum of resistance in it to favor the starting of the motor. As the arm 14 there- 40 after moves up, an increasing amount of resistance will be cut into the field circuit; since while the initially very small fraction of the current which flows up through the resistance 18 and thence through the connection 19' to the lead 20, will be slightly increased for each of the first few upward steps or successive engagements of the contact 16 with the plates 17, the current which flows through the wire 19' is at such times 45 in any case almost negligible, whereas the bulk of the current which had at first flowed from the lowermost plate 17' to the wire 20, while encountering practically no resistance other than the field coils, has a progressively 50 and quite rapidly increasing resistance introduced into its partial circuit or branch, as the arm 14 ascends. 55 When the plate 17 corresponding substantially to the point 18' is reached by the contact 16, however, the resistance in the two branches of the circuit leading to the wire 20 from this plate, will have become substantially equal if we except the auxiliary or additional resistance 19", provided in the 60 wire 19'. Continuous upward movement of 65

the arm 14 after passing a point somewhat above the point 18', depending on the amount of the resistance 19', on the whole tends to cut resistance out of the field circuit, so that when said arm reaches the position in which it is shown in full lines in Fig. 1, the connection between the corresponding plate 17 and the wire 19' offers a minimum of resistance and if it were not for the resistance 19", practically all of the current 70 would flow through this course. The resistance 19", however, provides the resistance in the circuit which it is desirable to retain therein at such time, and the motor will hence run as it normally should when 75 a single carrier is in course of transit through the line. Concerning the operation of the system when more than a single carrier is in course of transit, this will be discussed hereinafter. 80

85 The armature connections may be made as follows: From the positive lead 24 current will enter the arm 14 or a conductive portion thereof, and will pass therethrough to the contact 25 and after the arm in its initial upward movement has brought contact 16 into engagement with the plate 17', as above described, this contact 25 will be correspondingly engaged with the lowermost contact plate 26. Current will then flow 90 from this plate through a resistance 27 to an extended contact plate 28 from which extends a wire 29 which in turn is connected to the armature of the motor; a fixed resistance 30 being preferably inserted in this 95 wire.

The current emerging from the armature passes via wire 31 to the negative lead 23, completing the armature circuit.

As the arm 14 ascends, and during the 105 time that the contact 16 remains in engagement with the plate 17', it successively engages the contact plates 26 and thereby progressively cuts out the resistance 27 of the armature circuit, so that by the time the 110 contact 16 has by its upward movement commenced to vary the resistance in the field circuit, the armature circuit resistance will have become reduced to a determined amount offered by the resistance 30 and the armature winding. It will be understood that during the normal operation of the system and until the controlling apparatus actually commences to shut down the motor, the armature resistance will remain constant 115 and the control of the motor will hence be entirely determined by varying the resistance in its field circuit. 120

125 The means for thus initially actuating the rheostat arm 14 to establish normal operating conditions in the system will now be described. Assuming that a carrier such as that designated 32 has been inserted at 1' for despatch to the station B; such carrier will depress the lever 33 in a casing 34, to 130

close a preferably low voltage circuit across contacts 35. This completes the following circuit: Current flows from, for example, a battery 36 through a wire 37 to an arcuate contact 38, and since at such time the arm 14 will be in its lower position, said current will traverse a bridging contact 39 to a second contact 40, which while also preferably arcuate, may be shorter than the contact 38. 5 It then flows through the wire 41 to a wire 42 and from thence through the contacts 35 and their bridge 43, which is carried by the arm or lever 33, to a wire 44, whence the current passes to a wire 45 and through a 10 starting solenoid or magnet 46 to a wire 47 which leads back to the battery.

This energization of the solenoid magnet 46 draws up a bridge 48' to complete a circuit through the spring contacts 48, as follows: Current from the main positive lead 24 passes up through a short connection 49 and through the contacts 48-48' to a wire 50, thence through the main solenoid 51 to a wire 52 which is connected to the negative lead 23; a resistance 52' being preferably provided in the connection 52, to protect the solenoid 51. Thus, the instant that the magnet 46 is energized, the solenoid 51 will be correspondingly energized and its core 51' will be drawn up to thereby elevate a plate or table 53 mounted upon its upper extremity, and the first upward movement of this table causes it to press a roller 54 which is mounted upon the extremity of a 25 conductive spring 55 carried by the arm 14, upwardly until said spring is brought into engagement with a contact pin 56, which may project through the arm 14; this closure of contact between the spring 55 and 30 the pin 56 completing the following circuit: Current flows from the battery 36 through the wire 37 and contact 38 to the contact 39 and from this latter through a connection 57 to the contact pin 56. The current passes 35 thence through the spring 55 to a connection 58 which extends to a contact finger 59, which at such time is in engagement with an arcuate contact strip or blade 60. The current then passes through a wire 61 to the 40 wire 45, through a portion of which it flows to the starting magnet 46, whence it passes through the wire 47 back to the battery.

It will be understood from the foregoing that when the arm 14 is in its lowermost position its roller 54 will be held away therefrom by the action of the spring 55, since while the roller may even be in engagement with the table 53, as shown, the downward movement of the arm 14 is limited by a stop 45 62, to permit of interruption of contact between said spring 55 and pin 56; but that as soon as and in fact the very instant that the solenoid 51 is even momentarily energized, as by but a very short closure of the 50 low voltage circuit at the contacts 35, the

initial upward movement of the solenoid core 51' at once closes a maintaining circuit for the primary solenoid or magnet 46. This insures an upward movement of the core 51' through a determined distance and 55 the length of either or both of the contacts 38 and 60 determines the extent of this upward movement; since by the time that the arm 14 reaches the position in which it is shown in dash and dotted lines, designated 60 14', the contact fingers 39 and 59, or at least one of these, will be moved out of engagement with the corresponding contacts 38 and 60 to interrupt this maintaining circuit 65 through the primary solenoid whose armature or core will then drop to interrupt the circuit through the solenoid 51, to allow the core 51' of the latter to at once drop clear of the roller 54.

The spring 55 will aid the weight of the 70 roller in separating said spring from its pin 56 at such time, so that before circuit can again be completed through the contacts 39 and 59, pin 56 will have been separated from spring 55 and the primary solenoid will 75 thereafter remain deenergized until conditions hereinafter referred to are established.

It will be observed that owing to the fact that the contact 40 is preferably made shorter than the contact 38, the finger 39 80 may remain in engagement with contact 38 after it has ceased to bridge the contacts 38 and 40 with the result that while the maintaining circuit continues to be maintained until contact 39 is drawn out of engagement 85 with contact 38, the wire 41, for example, may be energized by the despatch of successive carriers from, for example, station A, only during the short time that contact 90 39 is thus able to bridge contacts 38 and 40; but that after it has been freed from the contact 40, and until contact is reestablished again at this point, the insertion of carriers into the line will not cause current to flow 95 through the wires 41 and 45, and such insertion of carriers therefore has no direct 100 effect upon the primary magnet, which feature is believed to be distinctively new.

Incidentally, it may be here observed, that 105 one advantage in this resides in the fact that after the maintaining circuit has been broken by the disengagement of, for example, contacts 38 and 39, such maintaining circuit cannot normally be reestablished under any circumstances until contact finger 110 39 has moved back into engagement with contact 40 and hence while the system is being controlled by the carriers themselves during their passage through the line, normally no current can be uselessly expended 115 in energizing solenoids 46 and 51, as a result of the introduction of successive carriers into the line.

Let us now consider the effect on the system of the starting of the motor by the up- 120 125 130

ward movement of the solenoid core 51' in the manner above described. The field circuit is first made with substantially no resistance in it other than that of the field 5 itself, and immediately after this the armature circuit is completed with full resistance therein. Then, the armature circuit resistance is cut out more or less gradually and as rapidly as the motor will permit, after which 10 resistance is increasingly introduced into the field circuit to speed up the motor. This resistance is cut in just as rapidly as is concomitant with safety and as a result the motor is rapidly speeded up until it is running 15 at a rate materially in excess of what it should for the transmission of a single carrier under normal conditions. This speeding up, however, is but for a short time, since thereafter the resistance in the 20 field is progressively decreased to slow the motor down to its normal speed for said transmission of a single carrier. This momentary speeding up, however, is of advantage, in that the inertia of the air in the 25 tubes is more rapidly overcome than it would be if the motor were to be speeded up merely to a normal speed, or in other words, the establishment of a normal carrier transmitting flow of air is accelerated by this 30 action of the motor.

The exhaust pipe 9 has extending therefrom a pipe 63 in which preferably is located a valve 64, and the pipe 63 opens at its outer extremity into the upper end of a cylinder 65 in which rides a piston 66. This latter may be of any suitable description and so will not here be more particularly considered, except that it should be stated that it is preferably provided with some 35 such means as a leather cup 66', for substantially preventing any flow of air around the piston, especially upon its downward stroke. The lower end of the cylinder is closed by a head 67 through which extends 40 a passage 68 which may be closed to any desired extent by a needle valve 69, or the like, to permit of the desired seepage of air into or out of the space beneath the piston, as the case may be. There is also provided 45 in this head a second passage 70 the opening of which into said space below the piston, is provided with a check valve 71, which in the exemplified construction is merely a small leather flap. The passage 70 is connected by a pipe 72 to a small casting or T 50 73 in which is a normally open vent 74. There is also provided a small cock or valve 75 for admitting a determined seepage of air into the pipe 72 when the vent 74 is 55 closed by a valve 76 mounted upon the upper end of the stem of the core of magnet 46.

In this connection it will be observed that the spring contacts 48, although they are preferably engaged by their bridge 48' be-

fore the valve 76 closes the vent 74, are capable of yielding sufficiently to allow said valve to tightly close this vent when the primary magnet is energized. 65

The piston 66 has depending therefrom a rod 77 which extends through the head 67 70 and has pivotally connected thereto at 78 a link 79 which in turn is pivotally connected to the arm 14; the connection at 78 between this link and rod being adjustable to permit of setting the arm 14 properly with respect to the contact plate 17' when the piston is in its lowermost position; a set screw 78' being set into the rod 77 when the proper adjustment has been attained. 75

During the upward movement of the arm 80 14 through the action of the solenoid 51, the vent 74 will be closed and the upward movement of the piston 66 by the thrust exerted against its rod through the link 79, will be retarded by the formation of a partial 85 vacuum below the piston. By a proper adjustment of the needle valve 69 and cock 75, piston 66 may therefore be caused to ascend at the rate desired, this rate of course being as rapid as is consistent with the preventing 90 of burning out of the motor by a too rapid change of resistance in either its armature or field circuits; but for motors of relatively small size such as are used in connection with 95 pneumatic despatch tube systems installed in stores and the like, the time required for the ascent of the arm 14 from its lowermost position to the point where its solenoid core 51' drops downwardly therefrom as a result of the interruption of the maintaining 100 circuit, which preferably, by the way, occurs shortly after the maximum resistance 105 18 has been cut into the field circuit, will be but a very few seconds. It is usually sufficient to permit of this interruption of the maintaining circuit when the arm 14 reaches 110 its position 14' or thereabouts, since by such time the motor should have speeded up to establish a sufficient difference in pressure upon the opposite sides of the piston, to insure the continued operation of the system until the last carrier shall have emerged therefrom in the manner hereinafter described. 115

After the arm 14 has ceased to be sustained by the table 53, there will be a tendency for the arm and its associated parts to move downwardly toward their lowermost positions, but such movement is in any case retarded so that it must consume at least several seconds, owing to the fact 120 that air will be trapped below the piston 66 since the check valve 71 will at once close under such circumstances and no air can hence escape through the pipe 72, despite the fact that the vent 74 will at such time be 125 open. The trapped air can, however, slowly escape past the needle valve 69 and the adjustment of this valve will determine the

speed of descent of the piston. If no carrier whatsoever be present in the line, this downward movement of the piston and arm 14 will continue and the motor will gradually be shut down; but if any carrier be present in the line a sufficient load will be imposed upon the air current to create a sufficient rarefaction of the air in the space above the piston to enable the air at 10 atmospheric pressure therebelow to maintain such piston in position to hold the arm 14 substantially where it is shown in full lines in Fig. 1. Obviously, when a carrier is descending through a long drop in, for 15 example, a vacuum line, there is a tendency for the vacuum ahead of the carrier to be broken at such time and if the drop be of sufficient extent, the air in the tube in advance of such carrier may even attain 20 the pressure of the outer air or even indeed may in some cases be slightly compressed. Under such circumstances, the piston 66 will gradually descend but as it does so it will first cause resistance to be cut progressively 25 into the field circuit to speed up the motor, which will again rarefy the air in advance of the carrier with the result that the moment the carrier has passed around the bend at the bottom of this drop, if there be such 30 a bend in the line, said carrier need not even momentarily come to rest in the tube, as, for example, in the position in which it is shown in the tube 5, but will be continued on its way toward its destination; here 35 again effecting a saving of time.

Now if no provision were made to counteract the effect on the piston of this speeding up of the motor, and since the load of the carrier on the current of air is a relatively small one, there would be a tendency, 40 once the motor had thus been speeded up, to thereafter maintain the piston in its motor-operating position, regardless of whether there were a carrier in the line or not. A number of means can be employed to counteract this tendency; but the one which I prefer to use has been selected for this purpose because it peculiarly well adapts itself to counteract the motor at any 45 one of the varying speeds of the latter which may be determined by the position of the arm 14 when the latter is controlling the motor through the resistance 18.

At the extremity of the arm 14 is located a roller 80 which is adapted for engagement with a cam-acting operating arm 81 mounted on the stem 82' of the valve 82; the latter being shown in detail in Figs. 2 and 3. This valve may be in the form of 50 a hollow cylinder, the walls of which are slotted, as at 83 and 84 to permit of the passage of air in through a cock or valve 85 in amounts proportionate to the displacement of the operating arm 81 from the nor-

mal position in which it is shown in full 65 lines in Fig. 1, toward its extreme outer or valve opening position indicated in dash and dotted lines in said figure at 81'.

The air thus flowing through the valve 82 passes through a pipe 86 to the T 87 which 70 connects the respective portions of the pipe 63 aforesaid, and the cam on the arm 81 is so shaped as to cause the valve 82 to be cracked progressively more and more open as the arm 14 moves up from the position 75 in which, or shortly after which, it begins to cut resistance into the field circuit, until said arm reaches the position 14' aforesaid. Then as the arm moves farther up to progressively cut resistance out of the 80 field circuit, the valve 82 is correspondingly closed to the end that if no carrier be in course of transit through the line, a sufficient amount of air may pass the valve 82 to counteract the effect which would otherwise be exerted upon the piston 66 as a result of the speeding up of the motor at substantially a rate in excess of its normal operating speed which would be determined by the positioning of the arm 14 90 where it is shown in full lines in Fig. 1.

While the opening of the valve 82 in varying amounts may thus be depended upon to counteract the speeding up of the motor, when no carrier is in the line, it cannot 95 counteract the effect of the load of a carrier on the air current if such carrier is present in the line; and indeed when the motor is speeded beyond normal, if there is a carrier in the line at such time there 100 will be such a marked increase in the change of pressure in the air ahead of the carrier as to quite promptly cause the piston 66 to ascend to its normal operating position.

I shall now describe a feature which I 105 regard as of considerable importance and one which is of very general application to pneumatic despatch tube systems where a pressure responsive device is employed as a means for controlling the speed of the motor; so that I distinctly desire it to be understood that the construction now to be described or any equivalent thereof, is not to be regarded as being limited to a particular 110 construction or combination of elements 115 such as have been given herein by way of exemplification of certain other aspects of my invention.

Adjustably mounted upon the rod 77 is a frame 88, to which, in the construction 120 shown in Fig. 1, is attached a float 89. This is immersed in a body of liquid 90, which may, for example, be oil; the float being lightly loaded with shot 91, or the like, to the indicated position thereof, where 125 it together with its frame, would, if unattached to the rod 77, normally be sustained by the liquid, in equilibrium. The liquid

may be retained in an annular receptacle 92, which may be suspended by arms 93 from the cylinder 65. I prefer to have the receptacle annular so as to permit the link 79 to extend down substantially through the center thereof to practically obviate any turning moment upon the piston rod or stem 77, whereby it will allow the piston to move as frictionlessly as possible. The float is also 10 preferably so proportioned to its container and to the amount and weight of the liquid in the latter, as to cause the float to reach the point in its downward path where it will be fully immersed at or about the time 15 that the arm 14 reaches its position 14'. When the float is thus pressed down into the liquid and said arm is in said position thereof, there is a tendency for the float to raise the piston and arm but as the arm approaches the position in which it is shown in full lines in the figure, this tendency decreases until, if the piston, arm 14, etc., were 20 without weight, there would be no tendency for the float to move such parts farther upwardly.

When the piston is moved farther upwardly from this point, as a result of the presence of, for example, two carriers in the line, there is additional weight thrown 30 onto the piston stem, owing to the fact that the float is now being pulled up out of the liquid by amounts proportionate to this upward movement of the piston. Said upward movement of the arm 14 from its normal, 35 and as we may term it, single-carrier position, results in bringing the contact 16 successively into engagement with the plates 17 at the upper end of the series of these plates, and this progressively cuts additional 40 amounts of a resistance 94 into the field circuit of the motor, with the result that the latter is again speeded up, this time in correspondence with changes in pressure in the line normally occasioned by the presence of 45 two or more carriers simultaneously in course of transit therethrough.

This variable weight, or the equivalent thereof, which may be imposed upon the piston, it may be here noted, constitutes another 50 means for counteracting what I may term cumulative interaction between the means for establishing the air current and the governing or controlling device therefor, which acts responsively to variations in pressure 55 in the system. In other words, were it not for the provision of some means for increasingly opposing the upward movement of the arm 14 by its piston in response to the insertion, for example, of but a single additional carrier, when a first carrier is 60 already in course of transit, the upward movement of the piston resulting from this additional load on the air current, would cut resistance into the field to speed up the mo-

tor, which in turn would speed up the blower 65 and thereby correspondingly act upon the piston 66 through the intermediary of the air in the pipes 63 and 9, and this in turn would farther lift the piston to cut still further resistance into the field and to correspondingly increase the speed of the motor and blower, which in turn would again tend to lift the piston 66 still higher, with the result that further resistance would be cut into the field circuit, etc., until as a result 75 of perhaps but the introduction of only one additional carrier the piston 66 would be caused to move to the upper limit of its travel and the motor would be driven at a speed very much greater than is necessary 80 for the transmission of but two carriers in the line.

The fact, however, that as soon as the additional load on the line causes an upward movement of the piston 66 and arm 14, an 85 additional weight, or other means for counteracting to a limited measure the effect of the resultant speeding up of the motor, is imposed or caused to act upon the piston,—checks this progressively cumulative 90 action and only permits the piston to move up a small part of its remaining travel, just sufficient to cut in enough resistance in the motor field to take care of the small additional load on the line. 95

If a third carrier be introduced, while the other two are still in course of transit, there will be a still farther upward movement of the piston and arm 14 in correspondence with this variable additional load; but not 100 in excess of the service requirements.

As above intimated, I am aware of a large number of equivalents for the counteracting means in question and in Fig. 4 I have illustrated a modification which instead of using a float suspended from the frame 88', employs weights which may be of any suitable description, but which I prefer to provide in the form of balls 95—95', which may be strung on wires or cords 96, which are attached to the frame 88'. The casing or container 97 which receives and supports these weights as they are unloaded thereinto by the downward movement of the frame 88', may be supported from the cylinder 65 by a cylindrical inclosure 98. When the piston rod or stem 77 is in its lowermost position, all of the balls 95—95' may be in effect unloaded into the casing 97 which will then support said balls or weights, but as the rod ascends, it picks up a gradually increasing load, and if desired this load may be varied, by changing the size of the balls, as at 95', so that, for example, to move the arm 14 to its position 14', the piston may have sustained 110 to this point but the load of the small balls 95, and farther upward movement to speed 115 down the motor to normal operation thereof 120 125

for the transmission of one carrier or for additional subsequent speeding up of the motor following additional carrier insertions, the piston will then be loaded with successive balls 95.

The speed counteracting means which comprises the valve 82 and its operating cam may also be regarded as to some extent an equivalent means for the counteracting means just described; but as I have shown how the cammed control of a vent may be caused to counteract the effect of changing the speed of a motor in connection with one part of the apparatus, it would needless 10 burden the description of the invention to particularize concerning all of the various equivalents which may be used in lieu of the variable load devices, more especially described in this connection. It will be understood, too, that devices which are indeed generally considered as equivalents to weights are also very clearly within the purview of this phase of my invention.

The employment of either a float or a chain-like weight, affords an exceedingly simple construction which is admirably adapted to compensate for predetermined changes in pressure conditions in the system, the effect of which it is desired to counteract; while in so far as the travel of the arm 14 in connection with the resistance 18 is concerned, the venting valve which is first cammed open as resistance is cut in and thereafter is allowed to cam toward its closed position as said resistance is cut out, is probably as simple a device for this purpose as could be devised. Each of these devices therefore, while analogous in function, to a certain extent, are peculiarly well adapted to 30 accomplish the particular objects for which they are provided.

It may also be observed that by a proper adjustment of the valves 64 and 85, the wastage of air resulting from the cracking of the valve 82, may be reduced to a minimum and that this wastage of air normally only occurs when but a single carrier is in course of transit and certain conditions arise in the system which require a momentary speeding up of the motor, or a further action of the valve 82 during a very short period following the emergence of the last carrier in the line when the motor is correspondingly speeded up. At other times, when a single carrier is in course of transit with the motor operating at normal speed from this condition, or when the motor is speeded up as the result of the presence of two or more carriers in the line, there is not even this slight seepage of air through the pipe 86. It is for this reason that the upper end of the arm 81, adjacent its pivotal point is made arcuate about the point 15 as a center rather than to have cammed in this part of the arm again to

force the valve 82 open in correspondence 65 with the cutting in of the resistance 94; since while this might readily be done it would involve a more or less constant waste of air, even though this waste be small, during the normal operation of the system for one or more carriers; and further, the advantages resulting from the use of the float or the like would be lost.

The inward movement of the arm 81 by its spring 100 is limited by a stop 99, and the 75 shape and size of the slot 83 in the valve 82 may obviously be varied as desired to enable the counteraction of the variations in speed of the motor, when controlled by the resistance 18, to a nicety.

It will be understood that the weight of the piston, its stem, the float and its frame, the link 79 and the arm 14, will collectively be just sufficient to force the float down to the bottommost position thereof, in correspondence with the lowermost position of the arm 14; and that while after the float itself has been completely immersed there is but little further tendency for it to cause an additional thrust upwardly against the piston; 90 nevertheless the arms of the frame 88 may be so proportioned as of themselves to exert a slightly increasing upward thrust resulting from their immersion into the liquid and the consequent upward displacement of a small 95 but variable amount of the latter, depending upon the extent of immersion of said arms in said liquid.

As a result of the nearly balanced condition attained by this upward thrust exerted 100 through the arms of the frame 88 when the piston is in its lowermost position, the solenoid 51 need not be a strong one; since when its core commences to move upwardly thereinto, it encounters but slight resistance, 105 and while this resistance at first slowly increases, and thereafter somewhat more rapidly increases until the table 53 has been lifted to the position from which it will drop free of the roller 54, the solenoid in the meantime has substantially correspondingly increased its ability to pull up its core, as the latter moves farther and farther into the coil; so that even in this respect there is 110 a certain coaction between the float and the 115 operating solenoid.

Further, the operating or main solenoid 51 does not have to lift the arm 14 very far before the motor has been speeded to maximum and thereafter the system itself sustains 120 the arm, air being freely admitted through pipe 72 as required, while the solenoid core drops away not to go into service again until the motor has slowed down following the emergence of the last carrier, to a point where contact 39 bridges contacts 38 and 40 and only then or thereafter when a carrier is inserted for despatch through the line.

The provision of yielding springs for the contacts 48 also affords a maintenance of the circuit which energizes solenoid 51, for a fraction of a second after solenoid 46 is 5 deenergized; which permits the contacts 39-59 to clear contacts 38 and 60, or one at least of them, by a safe margin to insure against even a remote possibility of a maintenance of circuit at 55-56 and reestablish- 10 ment of this circuit at 38-39-59-60, by a too quick fall of the arm 14 after the table 53 starts to drop. As any descent of arm 14 is relatively slow and as the table 53 drops freely, the slight maintenance of contact at 15 48-48' insures the deenergization of solenoids 46 and 51 as soon as the arm 14 reaches its position 14'.

The primary or starting solenoid or magnet 46 is not only controlled from station A 20 when the apparatus is idle or substantially idle; but said magnet is also controlled in a similar fashion from station B; since the tube 5 is also provided with a casing 34, having contacts therein, similar to that shown 25 in detail in connection with station A, and these contacts are respectively connected to the wires 41 and 45 by wires 42' and 44'.

In general it may be stated that not only 30 does the float 89 possess advantages over mere weights such as are shown in Fig. 4, or the equivalent thereof, for reasons above indicated; but further by its very nature as a float in a body of liquid, it tends to steady the action of the apparatus and not to permit 35 mere momentary fluctuations in pressure to materially disturb the adjustment of the arm 14. Also the valve 64 by its presence in the connection leading to the pressure sensitive apparatus, acts to throttle down momentary pulsations so that these latter have to persist for an appreciable period of time, which of course is short but not merely momentary, before the piston and its associated 40 parts can have the positions thereof materially changed.

The operation of the system, in general, will now be considered.

Assuming that a carrier is to be despatched either from station A to station B 50 or vice versa, the closure of contacts in the casing 34 at the station from which the carrier is despatched effects an energization of the starting magnet 46 which promptly rises to close the vent 74 and complete the circuit 55 which energizes the main or operating solenoid. The very first part of the movement of the core of this latter closes the maintaining circuit for the primary or starting magnet, so that even though the closure of circuit 60 across the contacts 35 at one or the other of the stations has been but momentary, the system will start into operation.

The solenoid 51 presses the spring 54 up into engagement with its pin 56 and thereby 65 raises the arm 14, in so doing creating a

vacuum below the piston 66 and the setting of the valves 69 and 75 determining the speed of movement of the arm.

The motor is started by having its field circuit completed and then its armature circuit, which is completed immediately thereafter, has resistance cut out of it until the motor has been fairly started. Resistance is then cut into the field circuit until the motor has been speeded up beyond normal requirements for the transmission of the single carrier thus far inserted.

About the time that it has thus attained its maximum speed, so that the building up of the carrier transmitting flow of air 80 through the tubes has been accelerated, and the carrier started on its way, the maintaining circuit is broken by the separation of contact 39 from contact 38 and of contact 59 from contact 60, which results in the deenergization of the magnet 46, followed by the deenergization a fraction of a second later of the solenoid 51, which permits the table 53 to drop, breaking the maintaining circuit. The dropping of the valve 76 upon the deenergization of its magnet, at once admits air at atmospheric pressure through the pipe 72, so that if anything, there is a counter-acting tendency for the piston 66 to move upwardly rather than downwardly at this 90 time. Said piston thereafter, by reason of the presence of the load on the air current in the line, continues to move up until it has cut resistance out of the field to a sufficient extent to cause the motor to operate at a 95 speed which is above that required for the normal transmission of a single carrier.

During the time that the arm 14 was thus moving upwardly with its contact 16 successively in engagement with the plates 17, 105 at first by the upward thrust of the table 53 and latterly by the upward pull upon the rod 77, the valve 82 was at first gradually opened to permit of the requisite introduction of air to balance the increase in speed of 110 the motor, and thereafter was correspondingly closed as the speed of the motor decreased. When normal speed is attained, the valve 82 is entirely closed and preferably remains closed during any farther upward 115 movement of the arm 14 resulting from the imposition of additional loads on the carrier transmitting flow of air.

During the ascent of the arm 14 toward its normal single-carrier-operating position, the 120 float aided and favored this upward movement but to a less and less extent as the normal position of the arm was approached. When an additional carrier is inserted at either station, the consequent increase in load 125 on the air current raises the piston 66 and its attached float and rheostat arm; but as this movement occurs the float is lifted above its normal single-carrier-transmitting position, and this additional load upon the pis- 130

ton counteracts the tendency of the motor and blower to co-act with the piston and rheostat to unduly speed up the motor. As a result the motor speeds up only to an amount sufficient to take care of the additional load imposed on the line. Each successive carrier thus introduced, when carriers preceding it are still in course of transit or when a carrier or carriers are in course of transit through the other tube, correspondingly affects the setting of the controlling device and the motor is speeded up by just the amount required.

As each successive carrier is introduced there is no reenergization of the primary or starting magnet so long as the rheostat arm 14 has not moved down to a position where it is nearly ready to stop the motor; but rather the control of the motor is through the variations in pressure in the system resulting from the imposition of loads thereon.

When a carrier drops down through a considerable distance to more or less compress the air ahead of it, the pressure in the air above the piston 66 rises and the piston falls, its downward fall being retarded by the air trapped in below it, which can only escape past the needle valve 69. At such time as the arm 14 descends the motor speeds up and hence tends to again rarefy the air in advance of the carrier, to speed it on its way, while this speeding up of the motor is compensated for in so far as the pressure sensitive mechanism is concerned by the cracking of the valve 82. As soon as the load of the carrier is again felt upon the air current, which owing to this speeding up of the motor is almost at once, the piston 66 tends to move up again to restore the arm 14 to its normal single-carrier-transmitting position. The descent of the piston 66 occasioned by this drop of the carrier through a considerable distance in the line, is also increasingly opposed by the float as the latter is immersed more and more deeply into its bath. As the connection between what in the present case is an exhaust pipe and the pressure sensitive apparatus, is throttled down by the valve 64, the admission of air through the valve 82 need be but small indeed, being correspondingly throttled down by the cock or valve 85.

Assuming that several carriers are in course of transmission at the same time and that the arm 14 is at almost the upper end of its path of travel, with most or all of the resistance 94 cut into the field circuit and the motor correspondingly speeded up,—as a carrier emerges, to reduce the load on the line, there is a corresponding downward movement of the arm 14 to shut down the speed of the motor. Obviously, when such a carrier passes the valve 7' there will be a momentary inrush of air at atmospheric pressure into the pipe 9; but as the connec-

tion between said pipe and the pressure sensitive apparatus is throttled down by means of the valve 64, this pulsation cannot in any case greatly affect the disposition of the piston 66, especially since any abrupt downward movement of this latter is opposed by the air trapped therebeneath and by the inertia of the float and the liquid which it must displace when it moves downwardly thereinto.

When all of the carriers in course of transmission have emerged from the line, before the system becomes idle, its motor will first be speeded up for a short time and thereafter if no carrier be inserted in the interim, the resistance will be cut out of its field circuit and resistance will then be cut into its armature circuit to the end that if the system is arranged, as it preferably is, and as shown, to completely stop said motor, this end may be attained by the movement of the arm 14 to its lowermost position.

The herein described system is hence adapted to operate with substantial certainty, it being practically impossible in lines of even considerable length, to stall a carrier in the line, while if a carrier be heavily laden so that its frictional engagement with the tube is relatively great, not only will the apparatus continue in operation so long as this carrier is in the line at all; but further the very fact that the carrier is heavily laden, as for example if it be filled with coin or the like, will cause the motor to speed up to a sufficient extent to cause said carrier normally to travel toward its destination at a speed considerably in excess of that which would be imparted to it if the motor were not thus controlled, and yet by reason of the provision of the float or some one of the equivalents thereof, of which I am aware of many, this increased load on the line does not cause the motor to race in excess of the service requirements.

Having thus described my invention what I claim is:

1. A pneumatic despatch tube system comprising a line of transmission tubing, means to establish a flow of air through said line to propel a carrier, said flow tending to increase at the instant that it is unburdened of all carriers, and controlling mechanism comprising means, controlled by this change in the air current, for first causing a still further increase in the flow of air, through the line normally effective to propel any carrier which would otherwise tend to remain in the line and co-acting means to disestablish the carrier propelling current of air when no carrier is in the line to resist said further increased flow.

2. A pneumatic despatch tube system comprising a line of transmission tubing, means to establish a flow of air through said line to propel a carrier, said flow tending to in-

- crease at the instant that it is unburdened of all carriers, and controlling mechanism comprising means, controlled by this change in the air current, for first causing a still further increase in the flow of air through the line normally effective to propel any carrier which would otherwise tend to remain in the line and co-acting means to disestablish the carrier propelling current of air when no carrier is in the line to resist said further increased flow, said mechanism having pressure-responsive provisions to restore the normal flow of air through the line in place of disestablishing said air current when a carrier still is in the line.
3. A pneumatic despatch tube system comprising a line of transmission tubing, means to establish a flow of air through said line to propel a carrier, said flow tending to increase at the instant that it is unburdened of all carriers, and controlling mechanism comprising means, controlled by this change in the air current, for first causing a still further increase in the flow of air through the line normally effective to propel any carrier which would otherwise tend to remain in the line and co-acting means to disestablish the carrier propelling current of air when no carrier is in the line to resist said further increased flow, said mechanism having pressure-responsive provisions to also increase the air flow first mentioned, when a second carrier is inserted for transmission while the first is still in the line.
4. A pneumatic despatch tube system comprising a line of transmission tubing, means to establish a flow of air through said line to propel a carrier, said flow tending to increase at the instant that it is unburdened of all carriers, and controlling mechanism comprising means, controlled by this change in the air current, for first causing a still further increase in the flow of air through the line normally effective to propel any carrier which would otherwise tend to remain in the line and co-acting means to disestablish the carrier propelling current of air when no carrier is in the line to resist said further increased flow, said mechanism having pressure-counteracting provisions to permit its said co-acting means to become effective in spite of said further increased flow so long as the latter is unresisted.
5. A pneumatic despatch tube system comprising a transmission tube, mechanism to establish a carrier propelling current of air through said tube, and means to control said mechanism by a change in pressure in a part of said system, said controlling means having provisions for itself effecting a change in pressure in said part by its action on said mechanism, and a venting device operated by said controlling means to counteract the effect on the latter of said last mentioned change, to maintain said controlling means

responsive to changes in pressure in said part unoccasioned by its own action.

6. A pneumatic despatch tube system comprising a line of transmission tubing, an electric motor and pump for creating a carrier transmitting flow of air through said line, an electric circuit for operating said motor, a rheostat in said circuit for controlling the operation of said motor and pump, a pressure controlled device connected to said line and having an element thereof movable by differences in pressure upon different sides of said element, operative connections between said rheostat and said element whereby the rheostat is adjusted to speed up the motor and pump as the load of an additional carrier is imposed upon the air current traversing said line when said current is already propelling a first carrier, said imposition of said additional carrier upon the air current in said line causing an increase in the difference in pressures upon said different sides of said element, and means to impose a load on said element to in part only oppose the effect of said increased difference in pressures as said element responds to said increase.

7. A pneumatic despatch tube system comprising a line of transmission tubing, an electric motor and pump for creating a carrier transmitting flow of air through said line, an electric circuit for operating said motor, a rheostat in said circuit for controlling the operation of said motor and pump, a pressure controlled device connected to said line and having an element thereof movable by differences in pressure upon different sides of said element, operative connections between said rheostat and said element whereby the rheostat is adjusted to speed up the motor and pump as the load of an additional carrier is imposed upon the air current traversing said line when said current is already propelling a first carrier, said imposition of said additional carrier upon the air current in said line causing an increase in the difference in pressures upon said different sides of said element, and means to counteract the retroactive effect on said element of the speeding up of said motor and pump.

8. A pneumatic despatch tube system comprising a line of transmission tubing, means for establishing a carrier propelling flow of air through said line, a pressure controlled device connected to said line and having an element thereof movable by differences in pressure upon different sides of said element, operative connections between said element and said means to control the latter by a movement of the former, and means to impose a load on said element to in part only oppose the effect of an increased difference in said pressures which tends to move said element in a determined direction, said last mentioned means having pro-

visions to remove said load when said element is oppositely actuated by a decrease in the difference of said pressures.

9. A pneumatic despatch tube system comprising a line of transmission tubing, means for establishing a carrier propelling flow of air through said line, a pressure controlled device connected to said line and having an element thereof movable by differences in pressure upon different sides of said element, operative connections between said element and said means to control the latter by a movement of the former, and means to impose a progressively increasing load on said element to oppose the effect of progressively increasing differences in said pressures which tend to move said element disproportionately farther and farther in a determined direction.

20 10. A pneumatic despatch tube system comprising a line of transmission tubing, means for establishing a carrier propelling flow of air through said line, a pressure controlled device connected to said line and having an element thereof movable by differences in pressure upon different sides of said element, operative connections between said element and said means to control the latter by a movement of the former, a variably acting device, having a tendency for movement into a determined position and a tendency to increasingly oppose continued movement thereof out of said position, for correspondingly opposing a movement of said element, and operative connections between said device and said element to enable said device to transmit its said tendencies to said element.

11. A pneumatic despatch tube system comprising a line of transmission tubing, means for establishing a carrier propelling flow of air through said line, a pressure controlled device connected to said line and having an element thereof movable by differences in pressure upon different sides of said element, operative connections between said element and said means to control the latter by a movement of the former, a variably acting device having a tendency for movement into a determined position and increasingly opposing movement thereof out of said position in either of two directions, for opposing corresponding movements of said element, and operative connections between said device and said element, said device through the respective connections aforesaid, tending to hold said means in a normal operative position thereof.

12. A pneumatic despatch tube system comprising a transmission tube, a carrier to travel through said tube, means to establish a rate of flow of air through said tube adequate to propel said carrier, and co-acting mechanism to temporarily increase said flow of air beyond that which would nor-

mally follow the removal of the load of said carrier from the air current, when said air current is unburdened of said carrier.

13. A pneumatic despatch tube system comprising a transmission tube, a pump for creating a flow of air through said tube, a motor for driving said pump, a rheostat to control the speed of said motor and thereby of said pump, electrical connections for said rheostat and motor, a pressure-responsive device for controlling adjustments of said rheostat, connections between said device and said transmission tube whereby changes in pressure in the latter control the former, and a float having a bias for movement into a determined position thereof, operative connections between said float and a part of said device, said float by its said bias tending to set said device and rheostat respectively in adjustments corresponding to said position and variations in pressure in said tube variably acting through said device to at times resist said tendency and at other times to co-act therewith, according to the nature of said variations.

14. A pneumatic despatch tube system comprising a transmission tube, a pump for creating a flow of air through said tube, a motor for driving said pump, a rheostat to control the speed of said motor and thereby of said pump, electrical connections for said rheostat and motor, a pressure-responsive device for controlling adjustments of said rheostat, connections between said device and said transmission tube whereby changes in pressure in the latter control the former; a float having a bias for movement into a determined position thereof, operative connections between said float and a part of said device, said float by its said bias tending to set said device and rheostat respectively in adjustments corresponding to said position and variations in pressure in said tube variably acting through said device to at times resist said tendency and at other times to co-act therewith according to the nature of said variations, and co-acting means to initially adjust said rheostat to operate said motor and pump to create a carrier propelling flow of air through said tube and thereby to render operative said device and its float.

15. A pneumatic despatch tube system comprising a transmission tube, means to establish a flow of air through said tube, a device to control said means to vary said flow, pressure-responsive means to control said device, connections between said responsive means to control said tube, said pressure-responsive means having a part movable in a determined path one way or the other in accordance with variations in pressure in said tube, and means for imposing a variable resistance to the motion of said pressure-responsive means whereby to pre-

5 vent cumulative pressure-changing interaction of said device and flow-establishing means which would unduly displace said part for a minor variation in pressure in said tube.

16. A pneumatic despatch tube system comprising a transmission tube, a pump for creating a flow of air through said tube, a motor for driving said pump, a rheostat to 10 control the speed of said motor and thereby of said pump, electrical connections for said rheostat and motor, said rheostat having a controlling part and resistances to co-act therewith to automatically first speed 15 up said motor and thereby said pump just before the system is rendered idle for the transmission of carriers, and co-acting means to thereafter maintain said system operative for the transmission of a carrier 20 if said carrier be present in said tube when said pump is so speeded up.

17. A pneumatic despatch tube system comprising a transmission tube, a pump for creating a flow of air through said tube, a 25 motor for driving said pump, a rheostat to control the speed of said motor and thereby of said pump, electrical connections for said rheostat and motor, said rheostat having a controlling part and resistances to co-act 30 therewith to automatically first speed up said motor and thereby said pump just before the system is rendered idle for the transmission of carriers, means to thereafter maintain said system operative for the 35 transmission of a carrier if said carrier be present in said tube when said pump is so speeded up, and means to counteract the effect on said last mentioned means of the speeding up of said motor and pump, when 40 no carrier is in said tube.

18. A pneumatic despatch tube system comprising a transmission tube, a pump for creating a flow of air through said tube, a motor for driving said pump, a rheostat to 45 control the speed of said motor and thereby of said pump, electrical connections for said rheostat and motor, said rheostat having a controlling part and resistances to co-act therewith to automatically first speed up 50 said motor and thereby said pump just before the system is rendered idle for the transmission of carriers, means to thereafter maintain said system operative for the transmission of a carrier if said carrier be 55 present in said tube when said pump is so speeded up, and provisions for varying the speed of said pump in accordance with service requirements resulting from a plurality of carriers being simultaneously in 60 course of transit.

19. A pneumatic despatch tube system comprising a transmission tube, a pump for creating a flow of air through said tube, a motor for driving said pump, a rheostat to 65 control the speed of said motor and thereby

of said pump, electrical connections for said rheostat and motor, said rheostat having a controlling part and resistances to co-act therewith to permit of a reduction in speed of said motor when the system is to be rendered idle for the transmission of carriers, in accordance with a determined movement of said controlling part, means to retard said movement, and means, controlled by the current of air created by said pump, for 70 normally instituting said movement automatically after the emergence from said tube of the last carrier in course of transit therethrough, said last mentioned means having provisions to reverse said movement 75 of said part if the latter has resulted from a fluctuation in pressure in said tube caused by a temporary unloading of the air current when the last carrier has not yet emerged from the tube.

20. A pneumatic despatch tube system comprising a transmission tube, a pump for creating a flow of air through said tube, a motor for driving said pump, a rheostat to control the speed of said motor and thereby 90 of said pump, electrical connections for said rheostat and motor, said rheostat having a controlling part and resistances to co-act therewith to permit of a reduction in speed of said motor when the system is to be rendered idle for the transmission of carriers, in accordance with a determined movement of said controlling part, and means, controlled by the current of air created by said pump, for normally instituting said movement automatically after the emergence from said tube of the last carrier in course of transit therethrough, said last mentioned means including a timing instrumentality 95 and also provisions to reverse said movement of said part if the latter has resulted from a fluctuation in pressure in said tube caused by a temporary unloading of the air current which persists for a time period of less duration than that provided by said timing instrumentality.

21. A pneumatic despatch tube system comprising a transmission tube, a carrier to travel through said tube, means to establish a rate of flow of air through said tube adequate to propel said carrier, and co-acting mechanism to temporarily increase said flow of air beyond that which would normally follow the removal of the load of said carrier from the air current, when said air current is unburdened of said carrier, said mechanism including provisions for then gradually diminishing the flow of air through said tube after such temporary increase until said flow is completely disestablished.

22. A pneumatic despatch tube system comprising a transmission tube, a carrier to travel through said tube, means to establish a rate of flow of air through said tube ade-

quate to propel said carrier, and co-acting mechanism including means to retard a movement thereof, to first increase and then curtail said rate of flow normally upon the 5 emergence of said carrier, the duration of said increase being determined by said retarding means.

23. A pneumatic despatch tube system having therein a transmission tube, a pump 10 for creating a flow of air therein, a motor for driving the pump, and means for varying the speed of the motor in response to the load on the moving current of air, said means comprising devices acting on decrease 15 of load first to increase the speed of the motor, then to decrease it, and then to stop it.

24. A pneumatic tube system having therein a transmission tube, a pump for 20 creating flow in the tube, a motor for driving the pump, and means for governing the speed of the motor controlled on variation in the pressure in the tube, said means comprising devices for automatically increas-

ing the speed of the motor on decrease or 25 cessation of the load on the air-current in the tube during a predetermined time, said devices thereafter acting to stop the motor in the absence of renewed load on the air-current. 30

25. A pneumatic despatch tube system having therein a transmission tube, a pump for creating flow of air therein, a motor for driving the pump, and means for varying the speed of the motor in response to the 35 load on the air-current adapted to increase the speed of the motor on increase of the load, and devices actuated by the governor for increasing the motor on reduction of load, said devices acting to stop the motor 40 after a predetermined duration of such reduction.

In testimony whereof I have affixed my signature, in the presence of two witnesses.

CHARLES P. HIDDEN.
